CABINET FOR BOTTLE VENDING MACHINE

Charles E. Miller, Des Plaines, Ill., assignor to
Mills Industries, Incorporated, Chicago, Ill., a
corporation of Illinois

Application July 2, 1949, Serial No. 3,687

Term of patent 14 years

(Cl. D52—3)

To all whom it may concern:

Be it known that I, Charles E. Miller, a citizen of the United States of America, residing at Des Plaines, in the county of Cook and State of Illinois, have invented a new, original, and ornamental Design for a Cabinet for Bottle Vending Machine, of which the following is a specification, reference being made to the accompanying drawing, forming part thereof.

The figure is a perspective view of a cabinet for bottle vending machine, showing my new design. The side of the cabinet not shown is the same as the side shown and the back is plain and unornamented.

I claim:

The ornamental design for a cabinet for bottle vending machine, as shown and described.

CHARLES E. MILLER.
